UNITED STATES PATENT OFFICE.

OLIVER B. ROWLETTE, OF GRAND RAPIDS, MICHIGAN.

KNOCKDOWN SECTIONAL CASE.

1,067,376.

Specification of Letters Patent.

Patented July 15, 1913.

Application filed August 14, 1911. Serial No. 644,025.

To all whom it may concern:

Be it known that I, OLIVER B. ROWLETTE, a citizen of the United States, residing at Grand Rapids, in the county of Kent and 5 State of Michigan, have invented new and useful Improvements in Knockdown Sectional Cases, of which the following is a specification.

My invention relates to knockdown sectional cases, and its principal object is to provide such a case having improved means for detachably connecting its members together and an improved door mechanism: this, and other objects hereinafter appearing, are attained by, and my invention finds a preferable embodiment in, the structure hereinafter described and illustrated by the accompanying drawings, in which:

Figure 1 is a view in perspective of a case, 20 suitable for books, etc., and embodying my invention; Fig. 2 is a vertical section of the upper part of the same, on line 2—2 of Fig. 1. The other figures are enlarged detail views, viz.: Fig. 3 is a front edge view of 25 the upper portion of one of the section ends and part of its door; Fig. 4 is a like view of the end portion of one of the shelves; Fig. 5 is an end view of the upper portion of one of the doors; Fig. 6 is an inside view 30 of the upper part of one of the section ends illustrating, attached thereto, devices whereby the shelves are connected therewith, and the track on which the door moves; Fig. 7 shows a blank which is bent 35 to form said device and track; Fig. 8 is an end view of said blank when so bent; Fig. 9 is a horizontal section of part of said device on line 9—9 of Fig. 3; Fig. 10 is a plan view of the dowel connection between adjoining section ends; Fig. 11 is a vertical section of the same on line 11—11 of Fig. 40 10; Fig. 12 is a top plan view of the device attached to the shelves for connecting the same with the section ends; Fig. 13 is a side 45 view of the same; Fig. 14 is a sectional view of the same on line 14—14 of Fig. 12; and Fig. 15 is a like view of the same on line 15—15 of Fig. 12.

The several sections or units of my case 50 have ends 1 and backs 2: the shelf 3 is common to adjoining sections, forming the top of the lower and the bottom of the upper, and is the principal part which detachably holds the case together. For this 55 purpose it is provided with coupling members 4 engaging coöperating coupling mem-

bers 5 with which the section ends 1 are provided on their inner sides near their upper ends: these coupling members 5 are of sheet metal, and a corresponding pair 60 are fastened as by screws 6 and 7, one to each end 1 of a section. The upper portion 8 of such members is in any suitable manner spaced away from the side of the section end so as to form a recess 9 between the 65 section end and such upper portion. This recess may be provided by the construction shown in Fig. 3. A screw hole through the member 5 for the screw 6 may be formed with depressed walls as particularly shown 70 in Fig. 9, whereby a countersink for the screw is provided as well as a filler portion 10 between the coupling member and the section end. The coupling members 4 are of sheet metal, and a corresponding pair are 75 fastened, as by screws 11, one at each end of a shelf. These coupling members are formed as shown in Figs. 12, 13, etc., by bending a sheet of metal to form a portion 12, adapted to engage or lie against the end 80 edge of the shelf, a supporting flange 13 at right angles thereto and beneath the shelf, and a downwardly extending flange or hook portion 14 adapted to engage with the portion 8 of the coupling member 5 by entering the recess 9, and to thus securely but 85 detachably connect the section ends and the shelf together. Suitable gaps 15 in the flange 14 admit the screws 6 and filler portions 10. 90

The doors 16 are provided at each end with a supporting roller 17 pivoted on a bracket 18 on the inside of the door and toward its upper edge. In opening and closing the door, its inner side near the 95 door's ends travels on a track formed by a horizontal flange 19 on the member 5. This flange has a downwardly curved forward end 20, as shown in Fig. 6, forming a stop for the roller and preventing its disengagement from the track, thus supporting and holding the door in place when in its closed position. The roller is positioned a sufficient distance below the upper edge 21 of the door, and near enough the door's inner side, 100 that the door shall travel inside the case in an approximately horizontal line in opening and closing, and is thus prevented from rubbing or engaging the shelf above. The track or flange 19 may be interrupted to 110 form a gap 22 just to the rear of the curved portion 20, through which gap the rollers

may pass; and thus the doors may be placed in position after the section ends are connected by the shelves. The coupling member 5 including the track 19 may be formed 5 from a sheet metal blank 23 in which the square aperture 24 is cut to provide for the gap 22: the blank is now bent on the dotted line 25 which forms the edge of the track, and then in the opposite direction on 10 the dotted lines 26, whereupon the blank assumes in vertical section the shape shown in Fig. 8: the extension 27 is now bent to form the curved portion 20. Suitable vertical grooves 28 on the inside of the section 15 ends and near their rear edges, and registering horizontal grooves 29 in the upper and lower sides of the shelves near their rear edges, detachably receive the four edges of the backs 2: and dowels 30 in one section 20 end adapted to enter slots 31 in the adjoining section end serve to detachably connect such adjoining ends: these slots may be elongated as particularly shown in Figs. 10 and 11 in the direction toward the front and 25 back of the case to allow for any unequal shrinking or expansion of the wooden section ends. Ball bearings 32 may be provided as shown to minimize the friction in opening and closing the doors: and suitable 30 tops 33 and bases 34 may be added as shown.

It will be seen that the coupling devices whereby the section ends and the shelf are connected are located entirely between the inner sides of such section ends, no part of 35 such coupling devices extending between the abutting ends of adjoining section ends.

Not confining myself to the details of construction shown and described, I claim:

1. A track for the door of a knockdown 40 sectional case formed from a metal plate 23 having an aperture 24 therethrough and an extension 27, by bending said plate on the line 25 and oppositely on the lines 26 and then bending the extension downwardly and 45 backwardly to form a stop, substantially as described.

2. A track for the door of a knockdown 50 sectional case formed from a metal plate 23 having an aperture 24 therethrough, by bending said plate on the line 25 and oppositely on the lines 26, substantially as described.

3. A track for the door of a knockdown

sectional case formed from a metal plate 23 having an extension 27, by bending said 55 plate on the line 25 and oppositely on the lines 26, and then bending the extension downwardly and backwardly to form a stop, substantially as described.

4. In a knockdown sectional case, a section end having a coupling member comprising a metallic plate spaced away from the inner side of said end and having a countersunk depressed portion pierced for attaching means and forming a filler portion to space said flange away from the section end, and a shelf having a coupling member adapted to detachably engage said plate to couple the shelf and the section end together and support the shelf by the section end.

5. In a knockdown sectional case, a section end provided on its inner side with a metallic plate having a coupling member and having also a horizontal track, a door 75 adapted to travel horizontally on said track and in one position to be swung, and a shelf having a coupling member adapted to detachably engage the first mentioned coupling member to couple the shelf and the 80 section end together and support the shelf by the section end.

6. In a knockdown sectional case, a section end having on its inner side a coupling member comprising a metallic plate spaced 85 away from the inner side of said end, a shelf provided with a metallic coupling member adapted to detachably engage said plate to couple the shelf and section end together and support the shelf by the section 90 end, said metallic plate having a horizontal track with a gap therethrough and a stop, and a door adapted to travel on the upper side of said track and having a member adapted to pass through said gap and to 95 engage the under side of said track and adapted to permit the door to swing when said member engages the stop.

In testimony whereof I have hereunto set my hand in presence of two subscribing witnesses.

OLIVER B. ROWLETTE.
